UNITED STATES PATENT OFFICE

JAMES F. HINES, OF CLEVELAND, OHIO

MOLD CONTAINER

Application filed May 16, 1928. Serial No. 278,127.

The present invention relates, as indicated, to mold containers and a method of making same. From time immemorial, foundries have experienced the greatest difficulty 5 in obtaining mold containers of exact size, and it is the primary object of this invention to devise a mold container (and a method of making same), which will be of the exact desired dimensions within almost infinitesimal limits. To the accomplishment of the foregoing and related ends, said invention, then, consists of the means hereinafter fully described and particularly pointed out in the claims.

15 The annexed drawing and the following description set forth in detail certain mechanism embodying the invention, such disclosed means constituting, however, but one of various mechanical forms in which the 20 principle of the invention may be used.

In said annexed drawings:

Fig. 1 is a perspective view of a mold container, certain parts having been removed for clarity of illustration, and a form 25 being shown in dotted outline; Figs. 2 and 3 are plan views of a fragment of said container, the facing members having been removed in Fig. 2; and Fig. 4 is a horizontal section through the same fragment.

According to the present invention a form 30 A shaped as a truncated pyramid is provided, and the container is built up about this form. In the said drawings, I have illustrated only a drag section, but it is to 35 be understood that the application of the invention to the cope section of a flask or to a jacket or to any other mold container will be substantially the same. The form A is built of metal, and is provided with removable 40 abutments (not shown) which may be placed at different points in the altitude of the form.

The abutments having been properly located, a pair of drag side plates 11 and a pair of drag end plates 12 of proper dimensions are assembled about the form, their lower edges resting on the said abutments. While it is desirable to have the side plates 11 and end plates 12 of exactly proper dimensions so that their adjacent ends will

be brought into close engagement when they are so assembled on the form, such exact dimensioning is not absolutely necessary, as will appear hereinafter. The side plates 11 and end plates 12 are preferably formed of 55 cast aluminum, having their inner surfaces completely finished before assembly and each of said members is provided at each end on its interior surface with a recess 13 arranged to communicate with and to cooperate with 60 the adjoining recess 13 of the adjacent part.

The side and end plates having been assembled in the above described manner, they are tightly clamped in position by any desired means, the lower ends of the recesses 65 13 are closed in a suitable manner and then molten metal is poured into the cavities defined by the recesses 13 and the form A. Metal which is so poured into the cavities may be lead or Babbitt metal, but I prefer 70 to use the same metal as that used in the plates themselves. Thus in the case above described, aluminum would be poured into the cavities.

The members 11 and 12 are allowed to 75 remain in position clamped about the form A until the metal 14 has cooled sufficiently to effect a firm and permanent bond, retaining the members 11 and 12 in position as a unitary integral drag, indicated generally 80 at 15. It will be noted that the inner face of the bond metal 14 assumes a smooth curve in accordance with the shape of the form A.

It will be noted that the form A is of sufficient height to permit the formation of a 85 cope section, the side and end plates thereof resting directly upon the upper edge of the drag section 15.

In Figs. 2 and 4 the specific construction of the recesses 13 is clearly indicated, and it 90 will be noted that the wall of each recess 13 is provided with a plurality of vertically spaced projections 16 which act to increase the bond area between the metal 14 and the members 11 and 12. It will also be noted that the 95 plates 11 and 12 are recessed as at 17 intermediate their ends in order materially to reduce the weight of the finished mold container.

In order to protect the relatively soft alu-

minimum of which the mold container is preferably formed, it is often advisable to provide facing strips of more resistant material for the upper and lower edges of the mold container. It may be preferable, therefore, to secure to the upper and lower faces of the mold container, strips of steel or similar resistant material. I prefer to provide these strips as a plurality of abutting sections and not as a single formed piece. Thus, as in the illustrated embodiment, I may provide four corner pieces 18 adapted to span the respective joints of the container, together with two end sections 19 and two side sections 20. 5

As the strips are secured to the flanges 22 of the plates 11 and 12, and as each corner section 18 is secured by screws 21 to one end plate 12 and one side plate 11, the corner pieces act as added reinforcements for the joints. Particular attention is called to the fact that the interior surface of each of the bonds 14 is flush at its edges with the interior surface of the abutting members 11 and 12, and intermediate its edges the same is rounded, whereby the mold container is formed with rounded rather than square corners. This is a feature of very great importance in that it materially facilitates the removal of the mold container from the wall and the maintaining of a clean mold, a feature long recognized as desirable but heretofore accomplished, if at all, only by extremely expensive operations. These advantages are obtained according to the present invention merely by properly contouring the corners of the form A on which the mold container is formed.

The advantages, from a standpoint of time economy, of the above described method of forming mold containers, will be apparent. Attention should be called, however, to the fact that the above described method is further advantageous in that it lends itself well to the building of outsize mold containers. Thus, for instance, if the mold A is designed primarily for building mold containers of one standard size, it will be possible to build upon said form mold containers of less size in almost any degree of difference, merely by placing the aforementioned abutments at higher points in the altitude of said form.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a mold-container, a joint comprising a pair of wall sections abutting at their ends and having recesses in their abutting ends cooperating to form a continuous recess open to the interior of the container and lying partly in each of said members, and a metal tie cast in said continuous recess and filling the same, said tie having a rounded interior surface.

2. In a mold-container, a joint comprising a pair of wall sections abutting at their ends and having recesses in their abutting ends cooperating to form a continuous recess open to the interior of the container and lying partly in each of said members, projections extending into said recesses, and a tie cast in said continuous recess about said projections, said tie having a rounded interior surface.

Signed by me this 11th day of May, 1928. 80
JAMES F. HINES.
